CLAIM

We claim, the ornamental design for a confectionary, as shown and described.

DESCRIPTION

FIG. 1 is a perspective view of a confectionary, showing our new design in a first embodiment;

FIG. 2 is a side elevation view of the embodiment shown in FIG. 1;

FIG. 3 is another side elevation view of the embodiment shown in FIG. 1;

FIG. 4 is a front elevation view of the embodiment shown in FIG. 1;

FIG. 5 is a rear elevation view of the embodiment shown in FIG. 1;

FIG. 6 is a top plan view of the embodiment shown in FIG. 1;

FIG. 7 is a bottom view of the embodiment shown in FIG. 1;

FIG. 8 is a perspective view of the confectionary, showing our new design in a second embodiment;

FIG. 9 is a side elevation view of the embodiment shown in FIG. 8;

FIG. 10 is another side elevation view of the embodiment shown in FIG. 8;

FIG. 11 is a front elevation view of the embodiment shown in FIG. 8;

FIG. 12 is a rear elevation view of the embodiment shown in FIG. 8;

FIG. 13 is a top plan view of the embodiment shown in FIG. 8; and,

FIG. 14 is a bottom view of the embodiment shown in FIG. 8.

The oblique line shading rendered on the outer portion of the confectionary shown in the Figures represents transparency or translucency of the outer portion.

Also, the broken lines shown in the drawings depict portions of the confectionary that form no part of the claimed design.
